United States Patent Office

Des. 210,277

Patented Feb. 27, 1968

210,277

HUMIDIFIER

Timothy C. Murphy, Columbus, Ind., assignor to Arvin Industries, Inc., Columbus, Ind., a corporation of Indiana

Filed May 31, 1967, Ser. No. 7,311

Term of patent 14 years

(Cl. D23—146)

Fig. 1

Fig. 3

Fig. 4

FIG. 1 is a perspective view of a humidifier showing my new design;

FIG. 2 is an end elevation thereof, showing the end opposite the end shown in FIG. 1;

FIG. 3 is a rear elevation thereof; and

FIG. 4 is a plan view thereof.

I claim:

The ornamental design for a humidifier, as shown.
